UNITED STATES PATENT OFFICE.

FRED W. BOCKSTEGE, OF EVANSVILLE, INDIANA.

DESIGN FOR A COMBINATION SIDEBOARD AND CHINA CABINET.

Application filed November 21, 1922. Serial No. 4,352. Term of patent 3½ years.

To all whom it may concern:

Be it known that I, FRED W. BOCKSTEGE, a citizen of the United States, residing at Evansville, in the county of Vanderburg, and State of Indiana, have invented a new, original, and ornamental Design for Combination Sideboard and China Cabinet, of which the following is a specification, reference being had to the accompanying drawing, forming a part thereof, which is a perspective view of a combination sideboard and china cabinet showing my new design.

I claim:

The ornamental design for a combination side board and china cabinet, as shown.

In testimony whereof I affix my signature.

FRED. W. BOCKSTEGE.
